UNITED STATES PATENT OFFICE.

JACOB R. JACOBSON, OF NEW YORK, N. Y.

HATBOX-MAKING MACHINE.

1,367,479.

Specification of Letters Patent.

Patented Feb. 1, 1921.

Application filed August 26, 1920. Serial No. 406,176.

To all whom it may concern:

Be it known that I, JACOB R. JACOBSON, a citizen of the United States, residing at New York city, county and State of New York, have invented certain new and useful Improvements in Hatbox-Making Machines, of which the following is a full, clear, and exact description.

This invention relates to improvements in box making machines, and has for an object to provide a device of this nature arranged to automatically form boxes, apply a covering or wrapper thereto, also apply bottoms to the boxes, and secure same in position. My improved machine is especially arranged to form boxes such as hat boxes or other circular or round containers having a bottom which is not integral with the body of the box.

I will now proceed to describe my invention in detail, reference being had to the accompanying drawings, wherein:

Figure 1 is a top plan view, the stapling device being omitted;

Fig. 2 is an enlarged sectional end view looking from the left in Fig. 1, the section being taken on line 2-2 in Fig. 1 certain other parts being omitted;

Fig. 3 is an enlarged fragmentary sectional view, the section being taken on a line 3-3 in Fig. 1;

Fig. 4 is a similar view, certain parts being omitted;

Fig. 5 is an enlarged sectional detail view, illustrating the gripper for the blank to form the box;

Fig. 6 is a fragmentary longitudinal sectional view the section being taken on a line 6-6 in Fig. 5;

Fig. 7 is a sectional detail view, illustrating the cutter for the wrapper for the box;

Fig. 8 is a detail face view of the magazine for the bottoms of the box, the ejector therefor being also illustrated;

Fig. 9 is a diagrammatic sectional view, illustrating a bottom as having been dropped into position at one end of a box;

Fig. 10 is a fragmentary sectional detail view of one end of the winding drum and associated parts, the section being taken on a line 10-10 in Fig. 3;

Fig. 11 is a diagrammatic view, illustrating the driving mechanism for the winding drum;

Fig. 12 is a similar view of the driving mechanism for the box shifting mechanism;

Fig. 13 is a diagrammatic view illustrating the folding mechanism for the binder to secure the bottom in place, also the end supports for said bottom; 60

Fig. 14 is an enlarged sectional view, illustrating one of the end supports, the section being taken on a line 14-14 in Fig. 13;

Fig. 15 is a similar view, the section being taken on a line 15-15 in Fig. 13; 65

Fig. 16 is a fragmentary detail view, illustrating one form of stapling mechanism;

Fig. 17 is a sectional view thereof, the section being taken on a line 17-17 in Fig. 16, certain parts being illustrated in elevation; 70

Fig. 18 is a diagrammatic view, illustrating a portion of the wrapper for the box and binder for the bottom of the box;

Fig. 19 is a fragmentary sectional view, illustrating the stapled edges of the blank 75 after a box is formed;

Fig. 20 illustrates a portion of a form of staple which I may use;

Fig. 21 illustrates a perspective view of the folder for the bottom binder; 80

Figs. 22 to 24 are detail fragmentary views, illustrating the yieldable finger at end of push bar;

Fig. 25 is a fragmentary view, illustrating the releasable device to operatively connect 85 the winding drums and driving mechanism therefor; and

Fig. 26 is a detail view of a portion of the rack.

Referring to Fig. 1, my improved device 90 consists of a drum 26 sufficiently long to wind a sheet 27 of cardboard or the like into circular formation and also to support the formed body of the box while it is being wrapped and bottom applied thereto. 95 The sheet of cardboard is formed into the body of the box on the portion A of the drum while portion B supports the body of the box while it is being wrapped and bottom applied thereto. After the body of 100 the box has been formed, it will be moved to portion B by means of a slidable push-bar or transferring element, indicated by 28, operating in a guide way 28^a. The device is arranged so that the push-bar 28 105 will act to push a formed body from A to B after said drum has made one complete revolution, to completely wind a sheet into proper formation for the body of a box. However, before the box is pushed from 110 A to B, a stapling device 29 will act to secure the end of the wound sheet together.

The ends of the sheet are indicated by 30 and 31 in Figs. 16 and 17, also the stapling device 29. After the box has been pushed from A to B, a wrapper 32 will be applied 5 to the box (see Fig. 4), but before the wrapper is applied, a bottom 33 will be placed in position (see Fig. 14, in which the body of a box is indicated by 34). After the bottom has been placed in position, the 10 said wrapper 32 and a binder 35 to secure the bottom in position will be simultaneously applied. In Fig. 18, I have illustrated a portion of a wrapper and binder as they will appear when fed to the body 15 of a box and the applied bottom. The wrapper will, of course, have paste applied to the under surface thereof, as will also the binder by means of a pasting roller 36, over which they travel, said roller 36 operating 20 in a pan 37, containing paste, indicated by 38. The wrapper is reeled off a roll 39 and the binder off a roll 40 over an idler 41. The roll 39 is carried by a pivoted frame 42 to facilitate the mounting of the rolls 25 (see Fig. 4). The frame may be swung outwardly, as indicated by dotted lines, and the roll placed in the boxes 43 and pushed downwardly against the tension of the spring 44 until the roll can be inserted under the roller 45. As the roll unwinds, 30 spring 44 will feed it upwardly. The binder 35 is fed along together with the wrapper and in contact therewith; in fact the binder passes between the wrapper 32 35 and pasting roll 36 along the adjacent edge of the wrapper and positioned so that a portion of the binder projects beyond the wrapper which projecting portion is afterward turned over to hold the bottom in 40 place, as indicated in Fig. 15. While the wrapper 32 and binder 35 are being fed in by the feeding roll 46 and pasting roll 36, said rolls being rotated to produce approximately the same surface speed as the drum 45 26, said binder 35 will be turned over, that is to say, the projecting portion to overlap the heretofore positioned bottom 33. To turn the said wrapper over, I provide a folder 46 (Fig. 21), which acts to turn the 50 projecting edge 35^a of the binder over and cause it to lie against the bottom 33, the folded in portion being afterward pressed firmly against the bottom by a roller 47 (Figs. 13 and 15), carried by a rock-arm 48, said arm being carried by a rock shaft 49 suitably supported by the frame 51 at one end, and by a pressing roll support 52 adjacent the other end. The folder 46 is carried by the rock arm 48 and is movable 55 with it for a purpose to be described. During the rotation of the drum 26 the binder will be caused to adhere to the bottom 33 and body 34 of the box by the binder roller 47 and a second roller 53, also carried by 60 the frame 48, said rollers being positioned

at a right angle to each other at the edge of the body portion of the box 34. During the application of the wrapper a roller 54 will act to maintain said wrapper smooth. The roller 54 is carried by an arm 55 on an 70 oscillatable rod 56 supported at one end by the frame 51 and at the other end by the opposite side of the frame of the machine, as can be seen in Fig. 2. The rod 56 also acts as one of the supports for the frame 75 52. The roller 54 rests upon the box and wrapper by gravity. The roller 54 at one end is tapered as at 54^a (see Fig. 2), to permit of the insertion thereunder of the body of a box when it is moved from A 80 to B. The rollers 36, 46 and 54 will be preferably rubber faced. When the drum 26 has made a complete revolution, the wrapper and binder will be cut from the main sheet by a knife 57, the cut off end 85 being pressed down upon the heretofore wrapped portion of the wrapper by said cutter, said cut off portion being indicated by 30^a (see Fig. 7). The knife 57 is pivoted at one end, as at 58, Fig. 1, to the 90 frame of the machine. The opposite end of the knife is connected by a link 59 to a rock-arm 60, operated by a shaft 61, carrying a shorter arm 62, which by means of a link 63 connects said arm 62 to an arm 95 64 on a rock shaft 65 operable by a lever 66; shaft 65 also operates other devices to be hereinafter described. It may here be stated that the operation of shaft 65 operates the knife 57, controls the operation 100 of drum 26 and associated parts, also controls the operation of the transferring device or push-bar 28. The function of the rollers 67 on frame 52 is to press the sheet 27, out of which the body of the box is 105 formed firmly against the drum 26 during the operation of rolling the sheet into box form. To facilitate the application of a sheet 27 to the drum 26 at A, I provide feed rollers 68 and 69, carried by the shafts 110 70 and 71, respectively, which shafts also carry the feed roller 46 and pasting roller 36. The shafts 70 and 71 are connected by intermeshing gears 72 and 73. The shaft 71 is operated by means of a thereby carried sprocket wheel 74 and chain 75, which in turn is operated by a sprocket wheel 76 on a sleeve 76^a on a supporting arm 77. The sprocket wheels 76 and 74 will be proportioned to operate the rollers 46, 47, 68 120 and 69 at approximately the same speed as the drum 26, that is to say surface speed. The drum 26 is carried by the sleeve 76^a and is operated at the will of the operator and makes but one revolution, that is to 125 say, one revolution of the drum will wind a sheet 27 into box form, after which the drum will come to rest. The arm 77 rotatably supports the sleeve 76^a, the said arm being in turn supported by pillar blocks 130

78 and 79 (see Fig. 2). The support 77 is not rotatable. Movement is transmitted to the sleeve 76^a by means of a disk 80, secured thereto, a gear 81 loose upon said sleeve, 5 an idle gear 82, and a driven gear 83, operated by a pinion 84^a, which in turn is operated by a belt 84 and clutch pulley 85, the shaft 86 for gear 84 and clutch pulley 85 being suitably supported by bearings 87 and 88. The gear 83 is loosely carried by a shaft 89, suitably supported in bearings 90 and 91. The shaft 89 carries a bevel gear 92 and a friction disk 93, which co-operates with a second driving disk 94 on shaft 95 10 carried by bearings 96 and 97. The shaft 95 is operated by a thereto attached gear 98 meshing with a driving gear 99 on shaft 86. It will be obvious that shaft 89 is driven by shaft 86 through the medium of the 15 friction disks 93 and 94. The gear 92 on shaft 89 meshes with a similar gear 100 on shaft 101 which shaft also carries a spur gear 102 meshing with a rack 103, which carries the push rod 28. Shaft 101 also 20 carries a sprocket 104, which by means of a chain 105 actuates a wiper 106 (see Fig. 2), carried by a shaft 107 supported by bearings 108 on the magazine 109 for the bottoms 33 for the boxes. The shaft 107 25 is operated in one direction only by means of a pawl 104 carried by the sprocket 110 loosely mounted on shaft 107. The pawl 104 engages a ratchet 111 to shaft 107. When chain 105 is operated, as per arrow 30 112, Fig. 2, the wiper 106 will have imparted thereto a complete revolution. This will take place while the pusher 28 is moving a formed box body from A to B. While the pusher is returning, pawl 104 will jump 35 the teeth of the ratchet 111, and wiper 106 will not operate. While a box body is being moved from A to B, a bottom 33 will be fed by the wiper 106 downwardly out of the magazine and will drop into place at 40 the end of drum 26 (see Figs. 8 and 9). A spring pressed follower 113 will maintain the bottoms in contact with stops 114 on the magazine 109, and will feed the pile outwardly when the outer one has been 45 fed or moved downwardly. To position the bottom relative to the box being fed toward it, I provide an apron 115 which is semi-circular (see Fig. 13), and alines with the outer surface of the body of the 50 box upon drum 26. The inner edge of the apron is curved downwardly as at 116 to facilitate the removal of a finished box from the drum 26 (see Fig. 2). In combination with the apron, I employ yieldable 55 positioning fingers 117, mounted upon posts 118 carried by the frame 51 (see Figs. 13 and 14). Each finger is maintained in position relative to the end of the box by a coil spring 118^a. Each finger carries an 60 arm 119, against which an adjusting device 65 120 bears, said adjusting device being carried by the frame 51 and is held in adjusted positions by a lock nut 120^a. The fingers 117 will be located in such position as to permit the bottom members to drop between them and the adjacent end of a box, 70 as indicated in Fig. 14. At the time that a bottom drops into place, rollers 48 and 53, also folder 46, will be positioned in alignment with the drum 26, as indicated by full lines, Fig. 13. As will hereinafter appear, 75 a bottom will be fed with portions during the shifting of a box body from A to B, but will drop into place before said body has been entirely fed onto portion B. When 80 the box body comes to rest upon portion B, it will be in contact with the bottom which has dropped into place. By manipulating the adjusting device 120, the position of the fingers 117 relative to the adjacent end of drum 26 can be adjusted so as to regulate the space for the passage of a bottom. When a completed box is pushed off the drum, the fingers 117 will yield or move outwardly to permit the box to be 85 moved off the drum 26. A completed box will be pushed off drum 26 by a body member when said member is pushed from portion A to portion B. 90

Referring to the means to operatively connect the drum 26 with gear 81, said means consists of a pawl 121 carried by gear 81, which is loose upon sleeve 76^a, to engage one of any of a series of notches 122 formed in the flange 123 of disk 80 (see Figs. 10 95 and 24). The pawl 121 will be pressed outwardly by a spring 124. The pawl 121 will engage a notch 122 throughout one revolution of the drum 26, means being provided to cause the drum to cease operating 100 after one revolution has been completed, said means consisting of a rock arm 125, Fig. 3, pivoted as at 126 to a bracket 127. The rock-arm 125 carries a nose-piece 128 to engage a notch 129 in a disk 130 carried by 105 the sleeve 76^a (see Fig. 10). The disk 130 is normally engaged by the rock-arm 125 and held against rotation; hence drum 26 will be normally held stationary. While 110 drum 26 is stationary, pawl 121 will jump the notches 122, as the gear 81 will be constantly in motion. When the drum 26 is to be rotated, arm 125 will be withdrawn from engagement with disk 130 by means of the hereinbefore mentioned lever 66 on shaft 115 65. The device will be regulated so as to cause the nose-piece 128 to be withdrawn from the notch 129 to an extent just sufficient to clear the periphery of the disk 130 say for instance one thirty second of an 120 inch. As soon as nose-piece 128 leaves its notch, disk 80 will be rotated by the pawl 121. As soon as the drum 26 starts to rotate, the lever 66 may be released, and arm 125 will rest against the disk 130. When 125 130

notch 128 comes to a position in line with the nose-piece 129, spring 131 will pull arm 66 toward the left, thereby causing the nose-piece 129 to engage notch 128 when said disk 5 130 and drum 26 will be brought to rest. Simultaneously with the operation of arm 125, friction disk 94 will be operated, also cutter 57 and rock-arm 48. In other words, when arm 66 is operated, shaft 65 will be 10 rocked thereby drawing friction disk 94 to the right of the axis of the shaft 89 (see Fig. 1), nose-piece 129 will be withdrawn from notch 128, cutter 57 will be operated to shear the wrapper, and binder and rock-arm 48 will be moved to the full line position in Fig. 13. When the drum 26 is at 15 rest, rock arm 48 will be in the dotted line position shown in Fig. 13, or out of alignment with the drum 26, because while the 20 drum is at rest, a formed body will be moved from portion A of drum 26 to portion B, and a completed box at B will be pushed off by the oncoming box body; therefore, roller 47 will have to be out of the 25 path of movement of the box. The function of the friction drive represented by disks 93 and 94 is to operate the rack 103 for the pusher, or in fact the pusher, firstly to the right in Fig. 1 to move a formed box body 30 from A to B, while the drum 26 is stationary and then to return the pusher while the drum is rotating to form another box-body at A, and finish a box at B. The push-rod 28 carries a yieldable finger 132, which 35 operates in a slot or channel 133 while moving in one direction in the drum 26 while the drum is stationary. When the drum starts to rotate, the finger 132 being in the position shown in Fig. 2, will be knocked down 40 (see Fig. 23), and during the return of the push-bar, the said finger will slide over the surface of the undergoing formation into a box body. The finger 132 is pivotally mounted in the push bar 28 and is held in 45 normal position (see Fig. 22), by a spring 134 (see Fig. 24).

To cause a sheet 27 to be carried around by the drum 26, I provide a gripper 135 (Figs. 3 and 5), which is actuated by a 50 spring to grip a sheet and by a cam spot 137 on a disk 138 to release said gripper, and also to hold it open. The disk 138 is secured to the fixed rod or support 76. When drum 26 is at rest, gripper 135 will 55 be open, being moved into such position by the cam spot 137. After a sheet 27 has been inserted between the gripper and drum (see Fig. 3), and the drum started, roller 139 will roll off the cam spot 137 and said gripper 60 will be caused to engage the sheet by spring 140. The gripper 135 is pivotally connected to the drum 26 at 141. During the rotation of the drum the sheet will be pulled around by the gripper 135, but will 65 be released as soon as the drum has made

one revolution in order that the box-body can be pushed away. While the sheet 27 is being rolled, it will be maintained smooth and close against the drum by rollers 142 carried by frame 52. After the drum 26 has 70 completely rolled a sheet, I provide means to secure the overlapping ends of the sheet together (see Fig. 17). In this instance, I have illustrated a stapling device hereinbefore referred to by 29. The stapling device 75 acts to drive staples, indicated by 143, through the overlapping ends of the sheet to secure the sheet in box form (see Fig. 19). The stapling device, which I have illustrated, is more or less diagrammatic, it 80 being on the order of a well device for stapling sheets of paper; at any rate it consists in this instance of two plungers 144 actuated by cams 145, carried by a shaft 150, operated by a sprocket wheel 151, a chain 152 and a sprocket 153 on shaft 70. The proportion of the sprocket gearing will be such as to cause cams 145 to rotate in unison with drum 26. Just before drum 26 completes one revolution, the plungers 144 will 90 start to descend and slightly before the said drum comes to rest, two staples, in this instance, will have been sheared off the strips 154, Fig. 20, and caused to contact with the rolled sheet. During the final movement of 95 the drum the staples will be driven through the overlapped ends of the sheet and be clenched by the anvil portion 155 in the drum 26, whereby the said overlapped ends of the rolled sheet will be secured together. 100 The strip 154 will be fed forward upon the return stroke of the plungers by a pawl 156 carried by a rock-arm 157, said arm being actuated by a projection 158 on the plungers 144. The casing 158 for the stapling device, 105 in this instance, is carried by the frame 51 by means of cross-brackets 159. In order to operate rock arm shaft 49, I provide same with a depending arm 160, which by means of a link 161 connects said shaft with a de- 110 pending arm 162 on shaft 65. To operate the friction disk 94, I provide shaft 65 with an upstanding arm 163, which by means of a link 164 is connected to a lever 165, said lever, by means of a link 166, carrying a 115 fork 167, actuates or moves disk 94 longitudinally of shaft 95, said fork engaging an annular groove 168 on the hub 169 of said disk 94. The lever 165 is provided for the purpose of positioning disk 94 relatively to disk 93 to produce the proper movement upon the part of the push-bar 28. In other words, when nose-piece 128 is in push bar, it moves to the right (Fig. 1), and to the left when nose-piece is out. The cutter 57 per- 120 forms two functions that of severing the sheet and binder and also to force the severed end down upon the box body upon the drum 26 at position B. To accomplish this latter feature, said cutter will be formed 130

with a relatively broad shoe 170 (see Fig. 7). As cutter 57 is operated after the drum has ceased rotating, there would be a loose end to the wrapper, and I prefer to apply the 5 said loose end to the box by means of the cutter. When the cutter descends, it will not only sever the sheet, but will also force the loose end down upon the box, as indicated in Fig. 7. When the drum is again 10 started, feed roller 46 will feed the sheet ahead under squilgee roller 54. Drum 26 will be in motion for a slight distance before the fed in sheet will contact therewith; hence, when the drum comes to rest, there 15 will be a small portion of the box, which is not covered by the wrapper, the so to speak bare portion will be covered by the hereinbefore mentioned loose end indicated by 171. The portion of the binder carried by the 20 loose end may be pressed down upon the bottom of the box by the fingers or otherwise, or it may be cut off. The push-bar 28 will act, while the drum 26 is stationary, to move a box-body from A to B, but will 25 return while the drum is rotating. The knife 57 operates when shaft 65 is rocked through the action of spring 131 to cause nose-piece 128 to engage slot 129 to stop the drum. When drum is started, by pulling 30 lever 66 toward the right in Fig. 1, knife 57 will be raised to normal position. When nose-piece 128 is withdrawn from the notch 129, disk 94 will be moved from dotted position, Fig. 1, to full line position, in which 35 the push bar 28 will be moved back to normal position while the drum 26 is rotating. At this time cutter 57 will be up, and rock-arm 48 in, as per full lines, Fig. 13. When nose-piece moves into notch 129 again, disk 40 94 will be moved back to dotted position, Fig. 1, and push bar 28 will then move to the right in Fig. 1, and push the formed box body from A to B. At the same time cutter 57 will act, and rock-arm 48 will move out 45 to dotted position, Fig. 13. There will be enough space between the body of a box at A and a completed box at B to permit the cutter to operate before the formed body commences to move the completed box off. 50 The stroke of the push-bar 28 will be sufficient to accomplish this result; in other words, the stroke of the bar will be greater than the length of a box.

To operate the device, a sheet 27 will be 55 fed by hand or otherwise to the gripper 135. The lever 66 will then be pulled in the direction of arrow, Fig. 3, after which the drum will start and the push-rod 28 will move toward the left Fig. 2. After a complete revolution has been made, the drum 60 will stop and the rolled sheet stapled. As soon as nose-piece enters notch 129, cutter 57 will operate and arm 48 move out. This operation on the part of the cutter will be 65 an idle one at the commencement of the op- eration of forming a plurality of boxes. The push-bar 28 will now move to the right and push the formed box body onto section B of the drum. A new sheet will now be fed to the gripper and the above operations 70 will repeat, excepting at this time, the body pushed onto B will be wrapped and supplied with a bottom. The next time a formed body is pushed onto B, the finished box will be pushed off. By means of my 75 improved device, I wrap a box and place a bottom therein while a box body is being formed. As soon as push-rod 28 pushes a box body clear of the gripper 135, a new 80 sheet 27 will be fed in by the operator and when said body is pushed into position on B, lever 66 will be operated to again start the drum. To prevent the push-rod from operating too far, I pivot the last tooth 180 in the rack 103 (see Fig. 26). When gear 85 102 clears the next to the last tooth 181, the rack will not move farther. When lever 66 is again operated, tooth 180 will mesh with gear 102, and the rack will return as explained. The push-rod 28 acts in feeding 90 direction while the drum is stationary and in the opposite direction while the drum is in motion. The complete travel of the push rod, in either direction, takes place during one revolution of the drum 26. 95 After the rod finishes an idle stroke, it will immediately commence an operating stroke for the reason that when it has completed an idle stroke, nose 128 will step into notch 129, thereby drawing disk 94 to dotted line 100 position, which will operate the push-rod to the right (Fig. 2).

What I claim and desire to secure by Letters Patent is:—

1. In a machine for producing circular boxes, a rotatable carrier arranged to roll a sheet of pliable material into a body portion, means to secure the ends of the rolled sheet together, means to automatically place a bottom in said body portion, means to apply a wrapper to the body portion, and means to apply a binder to said body portion and bottom. 105
2. In a machine for producing circular boxes, a rotatable drum arranged to wind a sheet of pliable material into a body portion, means to secure the ends of the sheet together after the body is formed, means to move the formed body to a position adjacent a wrapping element, means to automatically place a bottom member in position adjacent one end of the body portion after it has been moved from the wrapping drum, and means to apply a wrapper to the body member and also a binder to secure the bottom of the box to the body thereof. 115
3. In a machine for producing circular boxes, an intermittently operable winding element arranged to wind a sheet of pliable material into a body portion during one 120
- 125
- 130

revolution of said winding element, means to secure the ends of the wound sheet together at about the time that the winding element comes to rest, a wrapping device adjacent the winding element, and means to feed the formed body portion to the wrapping device while said winding element is at rest.

4. In a machine for forming circular boxes, a winding element to form a body portion, means to rotate same, a manually operable device to control the rotation of the winding device, a wrapping device, means to feed a wrapper to a formed body portion, 15 means to feed a formed body portion from the winding element to the wrapping device, and means controlled by the manually operable controlling device for the winding element to control the movement of said 20 feeding device.

5. In a machine for forming circular boxes, a winding element to form a body portion, means to rotate same, a manually operable device to control the rotation of 25 the winding device, a wrapping device, means to feed a wrapper to a formed body portion, means to feed a formed body portion from the winding element to the wrapping device, and frictional means controlled 30 by the manually operable controlling device for the winding element to control the movement of said feeding device.

6. In a machine for forming circular boxes, a winding element to form a pliable sheet into a body portion, a wrapping device adjacent the winding element, a roll of wrapping material adjacent the wrapping element, means to feed the wrapping material to a formed body portion, a cutter to sever 40 said material, means to arrest the rotation of the winding element when a complete revolution thereof has taken place, and means associated with the rotation arresting means for the winding element arranged to actuate 45 the cutter when the winding element comes to rest.

7. In a machine for forming circular boxes, a winding element to form a pliable sheet into a body portion, a wrapping device adjacent the winding element, a roll of wrapping material adjacent the wrapping element, means to feed the wrapping material to a formed body portion, a cutter to sever said material, means to arrest the rotation 50 of the winding element when a complete revolution thereof has taken place, means associated with the rotation arresting means for the winding element arranged to actuate the cutter when the winding ele- 55

ment comes to rest, means to feed a formed body portion from the winding element to the wrapping device, and means also associated with the rotation arresting means for the winding element to control the operation of the feeding device.

8. In combination with a rotatable carrier for forming the body portion of a box, means to locate a bottom member adjacent one end of the box, a pasting device, means to cause a wrapper and binder in combination to pass over and in contact with the pasting element, means to apply the wrapper to the box, and means to apply a portion of the binder to the side of the box and the remainder to the bottom for the box.

9. In a machine for forming circular boxes, a winding device to form a sheet of pliable material into a body portion, a wrapping device adjacent thereto, arranged to wrap a formed body portion while another 80 body portion is being formed, means to arrest the movement of the winding device after a complete body portion has been formed and means controlled by the rotation arresting means for the winding device, arranged to operate the cutter while the winding device is being brought to rest.

10. In a machine for forming circular boxes, a winding device to form a sheet of pliable material into a body portion, a 90 wrapping device adjacent thereto, means to feed a formed body portion to the wrapping device, and means to place a bottom member for the body portion in position to be applied to one end of the body portion while 95 said body portion is being fed to the wrapping device.

11. In a machine for forming circular boxes, a winding device to form a sheet of pliable material into a body portion, a wrapping device adjacent thereto, means to feed a formed body portion to the wrapping device, means to place a bottom member for the body portion in position to be applied to one end of the body portion while 100 said body portion is being fed to the wrapping device, means to feed a wrapper to the body portion after said body portion has been positioned at the wrapping device, and means to apply a binder to the body portion 105 and bottom member for the body portion.

Signed at New York city, N. Y., this 25th day of Aug., 1920.

JACOB R. JACOBSON. [L.S.]
